(57) **CLAIM**

The ornamental design for a spoon spreader, as shown and described.

DESCRIPTION

FIG. 1 is a perspective view from the top-side of our spoon spreader;

FIG. 2 is a perspective view from the bottom-side of the spoon spreader as shown in FIG. 1;

FIG. 3 is left side plan view of the spoon spreader shown in FIG. 1 and FIG. 2;

FIG. 4 is a top plan view of the spoon spreader shown in FIG. 1 and FIG. 2;

FIG. 5 is a handle end plan view of the spoon spreader shown in FIG. 1 and FIG. 2;

FIG. 6 is a spoon end plan view of the spoon spreader shown in FIG. 1 and FIG. 2;

FIG. 7 is right side plan view of the spoon spreader shown in FIG. 1 and FIG. 2;

FIG. 8 is a bottom plan view of the spoon spreader shown in FIG. 1 and FIG. 2;

FIG. 9 is a perspective view from the top-side of the spoon spreader shown in FIG. 1 and FIG. 2 in a folded configuration;

FIG. 10 is a perspective view from the bottom-side of the spoon spreader shown in FIG. 1 and FIG. 2 in a folded configuration;

FIG. 11 is left side plan view of the spoon spreader shown in FIG. 9 and FIG. 10;

FIG. 12 is a top plan view of the spoon spreader shown in FIG. 9 and FIG. 10;

FIG. 13 is a handle end plan view of the spoon spreader shown in FIG. 9 and FIG. 10;

FIG. 14 is a spoon end plan view of the spoon spreader shown in FIG. 9 and FIG. 10;

FIG. 15 is right side plan view of the spoon spreader shown in FIG. 9 and FIG. 10; and,

FIG. 16 is a bottom plan view of the spoon spreader shown in FIG. 9 and FIG. 10.

The broken lines shown throughout the drawings form no part of the claimed design.
